DESIGN FOR A COMBINED VALVE HANDLE AND ESCUTCHEON

James Fraser, Edge Moor, Del., assignor to Speakman Company, Wilmington, Del., a corporation of Delaware

Application April 26, 1939, Serial No. 84,563

Term of patent 14 years

To all whom it may concern:

Be it known that I, James Fraser, a citizen of the United States, residing at Hillcrest, Edge Moor, in the county of Newcastle and State of Delaware, have invented a new, original, and ornamental Design for a Combined Valve Handle and Escutcheon, of which the following is a specification, reference being had to the accompanying drawing, forming part thereof.

The figure is a perspective view of a combined valve handle and escutcheon, showing my new design.

I claim:

The ornamental design for a combined valve handle and escutcheon, substantially as shown.

JAMES FRASER.
